UNITED STATES PATENT OFFICE.

JUDSON L. THOMSON, OF SYRACUSE, NEW YORK.

RIVET.

SPECIFICATION forming part of Letters Patent No. 333,700, dated January 5, 1886.

Application filed November 13, 1885. Serial No. 182,695. (No model.)

To all whom it may concern:

Be it known that I, JUDSON L. THOMSON, of Syracuse, in the county of Onondaga, in the State of New York, have invented new and 5 useful Improvements in Rivets, of which the following, taken in connection with the accompanying drawings, is a full, clear, and exact description.

This invention relates to the class of rivets 10 which are converted into clinching-nails by a bifurcation of the shank, producing pliable clinching prongs which are readily bent over to fasten the rivet to the article to which it is to be applied.

15 The invention consists in an improved construction of the clinching-prongs, whereby they receive, first, a broad bearing and thus a more secure hold on the material on which the prongs are clinched; secondly, a gradual 20 taper from end to end, so that the flexibility is gradually increased toward their free ends, and thus the main portions of said prongs have the requisite stability to pass through the material to which the rivet is to be applied; 25 plied without bending in either direction, while the end portions of the prongs are sufficiently pliable to be clinched; and, thirdly, said prongs are furnished with broad chisel-points which readily penetrate the material 30 and at the same time present wedging-faces, which by the resistance of the material cause the ends of the prongs to bend over and back into the material.

My invention is fully illustrated in the annexed drawings, wherein Figures I, II, and III are side views of my improved rivet, taken at the edges of the prongs. Fig. IV is a side view taken at the flatside of the prongs. Fig. V is a transverse section on line $x-x$, and 40 Figs. VI and VII show the rivet clinched to the article to which it is applied.

h represents the head of the rivet, and a are the two clinching-prongs, each of which I flatten on opposite sides and arrange with its 45 flat sides directly opposite those of the other prong and with a space, b , between them. Said prongs I taper throughout their length in a plane at right angles to the flat sides.

The taper may be either wholly on the inner 50 side, as shown in Fig. I of the drawings, or

wholly on the other side, as shown in Fig. III of the drawings, or partly on the inner and outer sides, as represented in Fig. II of the drawings. Either construction will serve to gradually increase the flexibility of the prongs 55 toward the free ends thereof, and at the same time impart the requisite stability to the main portion of the prongs, as hereinbefore stated. The free ends of the prongs a form into broad chisel-points c by beveling the end portion of the prong either on the inner side, as shown in Fig. I of the drawings, so as to cause the prongs to automatically bend outward, as represented in Fig. VI of the drawings, or on the outer side of the prongs, as 65 shown in Fig. III of the drawings, and thus cause the prongs to turn inward during the process of forcing them through the article to which the rivet is applied, as illustrated in Fig. VII of the drawings. The said chisel-points present broad wedging-faces which produce the aforesaid automatic clinching of the prongs. The intermediate space, b , leaves the material between the two prongs intact, and thus greatly preserves the integrity of the 70 article to which the rivet is applied and strengthens the hold of the rivet, which hold is further insured by the flattening of the prongs.

Having described my invention, what I 80 claim, is—

1. A rivet having clinching-prongs each flattened on opposite sides and arranged with its flat sides directly opposite those of the other, with a space between them, as set forth 85 and shown.

2. A rivet having clinching-prongs each flattened on opposite sides and arranged with its flat sides directly opposite those of the other, and tapered throughout its length in a 90 plane at right angles to the flat sides, substantially as described and shown.

3. A rivet having clinching-prongs each flattened on opposite sides and arranged with its flat sides directly opposite those of the 95 other, and beveled to a broad chisel-point at the free end, substantially as described and shown.

4. A rivet having clinching-prongs each flattened on opposite sides and arranged with 100

its flat sides directly opposite those of the other, with a space between them, and tapered throughout its length and beveled to a broad chisel-point at the free end, substantially in
5 the manner specified and shown.

In testimony whereof I have hereunto signed
my name and affixed my seal, in the presence

of two attesting witnesses, at Syracuse, in the county of Onondaga, in the State of New York, this 10th day of November, 1885.

JUDSON L. THOMSON. [L. s.]
